GRAPHIC RECORDER

George H. Kallen, Santa Ana, Calif., assignor to Pro-totech Incorporated, Cambridge, Mass., a corporation of Massachusetts

Filed Feb. 13, 1964, Ser. No. 78,628

Term of patent 14 years

The single figure is a left side, top and front perspective view of a graphic recorder, showing my new design, the right side being substantially a mirror image of the side shown.

The rear, not shown, is flat and unornamented.

I claim:

The ornamental design for a graphic recorder, substantially as shown and described.
